UNITED STATES PATENT OFFICE

1,924,668

BANKING SWITCH CONSTRUCTION

George B. Wadsworth, Covington, Ky.

Application June 14, 1930. Serial No. 461,090

4 Claims. (Cl. 247—2)

This invention relates to banking switch construction and has for an object the provision of a switch box which is especially adapted for both independent and connected or banked installation.

Another object is to provide a box of the type referred to wherein the switch is independently mounted, front operated for effecting economy of space and removable as a unit.

Another object is to provide a box of the class referred to wherein the side walls are entirely removable, interchangeable and replaceable by a connector channel which permits of banking installation from either side of the box and at the same time provides for independent closure and access of each box.

Another object of this invention is to provide a box of the type referred to wherein the branch fuse circuits and their associated parts are mounted upon a swinging bridge structure hinged to a wall of the box independently of the lid and movable to a position which renders the branch fuse side of the box absolutely clear so that wiring between adjacent banked switches of the invention may be installed entirely without interference and affording heretofore unattained freedom for such work.

Another object is to provide a box of this kind wherein the meter testing switches are carried by the hingedly mounted branch fuse block and operated with novel simplicity in a minimum of space.

These and other objects are attained by the means described herein and disclosed in the accompanying drawings, in which:

Fig. 1 is a plan view of a box of the invention with the lid in open position to disclose the interior thereof.

Fig. 2 is a plan view of the top of the box showing the meter connection opening, the lid being again open to show the switch operating opening and fuse door opening therein.

Fig. 3 is an enlarged view taken on line 3—3 of Fig. 1.

Fig. 4 is an enlarged view taken on line 4—4 of Fig. 1.

Fig. 5 is a view taken on line 5—5 of Fig. 1 but having the side wall of the box removed and showing the hinged branch fuse mounting.

Fig. 6 is a perspective view of a removable side wall for the box.

Fig. 7 is a perspective view of a connecting channel and closing trough of the invention attached to a fragment of the box.

Fig. 8 is a view taken on line 8—8 of Fig. 1.

Fig. 9 is a view taken on line 9—9 of Fig. 1.

Fig. 10 is a perspective view of a pair of the boxes of the invention connected in banked arrangement with the structure shown in Fig. 7.

The box of the present invention provides for economy in manufacture as well as in installation and connection. It will be noted that the operating switch and line fuses are arranged in a small compact unit which is nevertheless entirely accessible and that the branch fuse mounting and its associated parts are not only compactly arranged but are so disposed as to be swung entirely out of the box. The box comprises an apertured top wall 15, a bottom wall 16 to which a flanged cover 17 is hingedly mounted and a pair of similar side wall 18 having flanges 19 on three sides thereof suitably slotted as at 20 to receive inwardly extending lugs 21 on the top, bottom and rear walls of the box. The resiliency of the sheet metal permits of sufficient spreading of the top and bottom walls 15 and 16 to position and remove the side walls. From the foregoing it will appear that either or both of the side walls 18 may be readily removed when the box is open, but that the lug and slot connection between them and the box effectively precludes inadvertent separation.

The connecting channel indicated generally as 22 comprises a base 23 and flanges 24 all of which bear substantially the same relation to one another as the flanges 19 on the side walls. The base 23 and flanges 24 have slots 25 therein positioned identically with the slots 20 in the flanges of the side walls 18 wherefore it follows that the connecting channel with the slots 25 adjacent each side may be connected to the box at either side by removing the side wall 18 and inserting the connecting channel. In bank installations as shown in Fig. 10 the adjacent side walls 18 of adjacent boxes would be removed and a channel 22 inserted in the adjacent ends of said boxes. It will be noted that the flanges 24 each have a substantially V-shaped slot 26 at the top. The closing trough, indicated generally as 27, comprises a single piece of formed metal generally V-shaped in cross section to seat in the slots and terminating at the top in a pair of parallel wall portions 28. Formed on the lower V-shaped portion and at each end is a pair of wings 29 which are adapted to embrace the outer faces of top and bottom walls 15 and 16 of the box. The ends of the parallel wall portions 28 are developed into ears 30 which are disposed above the tops of flanges 24 and embrace the inner faces of the walls 15 and 16. The closing trough is thus fric-

tionally retained in position and forms a closure across the top of the connecting channel. The groove or depression along the top of the closing trough forms a rabbet which receives the adjacent flanges of the adjacent sides of the two boxes connected thereby. It will be noted that the connecting channel and closing trough provide practically a side to side connection between adjacent boxes thus minimizing the length of the wires passing from one box to another and providing, together with the lids of the boxes, a positive closure for the space between boxes.

As will be noted in Figs. 1 and 5 a U-shaped metallic bridge 31 has a hinged connection at 32 on the bottom wall 16 of the box and is provided at the end opposite its hinged mounting with a hooked tongue member 33 which seats in a suitable aperture in a flange 34 struck inwardly from the top wall 15 to a position transverse thereto. A pair of insulating blocks 35 are seated in the U-shaped bridge and may be conveniently secured thereto by screws 36. The blocks 35 are provided with wells 37 in which suitable metallic fuse supporting shells 38 are disposed. The usual branch circuit terminals 39 are mounted upon projections 40 integral with the insulating blocks 35 and disposed well below the top level of said blocks.

A novel, inexpensive and compact meter testing switch is provided by extending a short conductor rod 41 with an insulating knob 42 at the top, through a perforation in a conductor strip 43 comprising part of one of the terminals 39. The rod 41 has an extended contact shoulder 44 from which extends a reduced threaded stud 45 for entry in a threaded perforation in a terminal strip 46. The stud 41 is shouldered above the strip 46 so that when the threads on the portion 45 are released the spring 47 will draw the entire stud 41 upward and clear of the strip 46 thus breaking the electrical circuit for meter testing purposes and precluding inadvertent connection of that circuit. The insulating blocks 35 are shouldered at 48 and the portion thereof projects somewhat above the top of the box and through an aperture 49 in the cover 17 when the box is closed. The fuses thus projecting through the cover are protected by a hinged lid 50 which swings on the hinges 51. At the fuse sockets, four in number, are rendered accessible without opening the cover 17 by unscrewing said the vertically hinged lid 50. The blocks 35 projecting above the shoulders 48 completely close the aperture 49 in the cover rendering it impossible to make any unauthorized connection with a terminal in the box while the cover is closed and suitably sealed.

The top wall 15 of the box carries on its interior face a pair of channel elements 52 for slidably receiving a flanged meter adapting plate 53 which in turn may carry a somewhat similar conductive secondary adapting plate 54. All of these plates are locked against removal by the cover 17 when in a closed position.

The line switch and fuse unit indicated generally as 55 in FIG. 1 comprises an insulating base block 56 having ways 57 for receiving incoming service wires and a combined insulating switch mounting and fuse base block 58 removable therefrom. An integral base 59 of insulating material has mounted therein a fixed

guide member 60 flanged as at 61 for receiving a flange plate 62 disposed transversely thereof. A reciprocating member 63 is mounted on the fixed guide member 60 and normally resists slideable movement thereon because of the arms 64 pivoted on suitable extensions of the fixed member and having their ends entering suitable slots in reciprocating member. The arms carry springs 65 which are compressed upon movement of the reciprocating member and, after the arms have been moved about their pivotal mountings past dead center the springs 65 exert their force to project the reciprocating member 63 rapidly and without further manual force. Spaced insulating members 66, disposed one on each side of the member 59 each carry a pair of resilient contact plates 67 the opposite ends of each pair serving when in a lowered position to form an electrical connection between contact plates 68 and 69. The cover 17 has an aperture 70 therein housed over by a dome 71 with a restricted opening 72 through which a hooked handle 73 projects. The baffle plate 62 seals the aperture in the dome and permits reciprocating movement of the hooked handle 73 through the closed lid for opening and closing the switch.

Perforate lugs 74 mounted exteriorly of dome 71 may be provided for receiving a suitable locking means such as a padlock hasp which may pass therethrough and through a perforation 75 in the handle 73 to preclude unauthorized manipulation of the switch.

From the foregoing it will be apparent that all operations including the manipulation of the switch are performed from the cover side of the box so that the boxes may be mounted in side by side connected relation in back installation without difficulty or inconvenience.

It will be noted that the relatively small insulating base 56 is the only member secured to the rear wall of the cabinet so that the rear wall is in substance practically clear for the reception of line, load, meter connection and branch circuit wires. These, as previously explained are readily placed and extended from box to box without difficulty because of the removable nature of the branch fuse mounting and switch and line base unit.

The channeled sub-base for the main switch unit receives the heavy service wires and suitable lead off connection (not shown) which are disposed in said channels and electrically connected with the switch contacts or blades.

I claim:

1. In combination a pair of switch boxes having entirely open adjacent sides, flanged covers for said boxes, a connecting channel extending between the open sides of the boxes, complementary lug and slot means on said channel and the adjacent portions of the boxes for removably connecting said channel and boxes and a cover for the channel frictionally engaging both boxes exteriorly and having a way therein for receiving the adjacent flanges of the covers of both boxes.

2. In combination with a pair of cabinets having entirely open adjacent sides and each provided with a flanged cover, of a U-shaped channel extending between the cabinets, complementary lug and slot means on said cabinets and channel for removably securing them together and providing unobstructed communication between the interior of said cabinets, the free ends of the channel being V-notched, a V-shaped closure cover seating in said notches and extending over

the open top of the U-shaped channel and having portions adapted to extend into the cabinet covers adjacent the proximate flanges thereof and means at the corners of said closing cover 5 frictionally engaging the ends of the cabinet's exteriorly below the flanges of the covers and precluding removal of the channel.

3. In a banking switch construction the combination of a switch box comprising a rear wall 10 and a pair of opposed side walls, a cover mounted on one of said side walls, a branch fuse structure hingedly mounted on the other of said side walls and extending to the first mentioned side wall, a switch mechanism mounted on the rear wall 15 adjacent one of said side walls whereby a free and clear open front wiring channel is provided adjacent the other side wall and beneath the branch fuse mounting and interchangeable end wall and connector channels removably mounted 20 on said rear wall and side walls.

4. In a banking switch construction the combination of switch boxes each comprising a rear wall and a pair of opposed side walls whereby entirely open ends are provided in the box, a 25

cover hingedly mounted on one of said side walls, branch fuse structure hingedly mounted on the other of said side walls and extending to the first mentioned side wall, switch mechanism on the rear wall adjacent one of the side walls to provide free open front wiring channel space adjacent the other side wall and beneath the branch fuse mounting, a channel member seated interiorly in adjacent open ends of adjacent boxes and provided with V-shaped notches at the top, a cover member for said channel comprising a V-shaped portion seating at opposite ends in the notches in the channel and having outwardly struck lugs at each side of each end for frictional engagement with the exterior surfaces of the side walls of said boxes, said cover member having vertical wall portions extending from the top of the V-shaped trough section and providing outwardly turned lugs frictionally engaging the interior faces of the ends of the said side walls, said trough portion and the vertical extensions thereof forming a closure for the channel and receiving the adjacent flanges of adjacent box covers. 80 85 90 95
